17 Claims. (Cl. 250—20)

This invention relates to superheterodyne radio receivers employing an automatic frequency-controlled oscillator by which more exact tuning of the radio receiver may be obtained, the principal object of the invention being to provide an improved automatic frequency-controlled oscillator for use in such a radio receiver.

In radio receivers employing devices of this nature, the frequency of the oscillator is controlled by the received and selected signal, so that if the user should mistune the radio receiver by some small amount, a control voltage is generated which modifies the frequency of the oscillator in such a way as to minimize the mistuning. For example, if the radio receiver were mistuned by say, 5 k. c., a control voltage might be generated which would shift the oscillator frequency by 4.90 k. c. in such a direction as to cause the receiver to be mistuned by only 0.10 k. c., which results in improved reception and also permits the use of automatic and remote control devices and the like, which heretofore have not been sufficiently precise to tune accurately and dependably a receiver of the superheterodyne type.

The primary object of the present invention is to provide a practical automatic frequency-controlled oscillator suitable for use in multi-band superheterodyne receivers and adapted for manufacture by commercial methods.

Another object of the invention is to provide an improved controllable oscillator employing a vacuum tube as a controllable impedance, and to provide means whereby this impedance may appear as a pure reactance from which the resistive component inherently present in vacuum tube circuits has been eliminated.

Another object of the invention is to provide a controllable oscillator employing a differential circuit including a plurality of vacuum tubes, which tubes operate as pure reactances and from which the resistive component has been eliminated.

Another object of the invention is to provide a controllable oscillator employing a vacuum tube circuit in which vacuum tubes are utilized as impedances and the impedance presented by the tubes is determined by the mutual conductance of the tubes, and to provide means for minimizing the change in effective impedance due to variations in the mutual conductance which might be caused by variations in the cathode temperature, anode voltage, aging of the tubes, and similar circumstances.

Still another object of the invention is to provide an automatic frequency-controlled oscillator

adapted to cause variation of the frequency with respect to the control voltage in a symmetrical manner about each side of the mean frequency.

Still another object of the invention is to provide an automatic frequency-controlled oscillator so arranged that frequency modulation due to hum pick-up and other extraneous signals which may be induced in the leads of the circuit, is minimized.

Another object of the invention is to provide a resonant control reactance for use in supplying a quadrature voltage to the control tubes in such a way that substantially uniform control sensitivity may be obtained over the frequency band within which the oscillator frequency may be established.

Other objects and features of the invention will be apparent from the following description and the accompanying drawings.

In the drawings:

Fig. 1 is a schematic block diagram of a superheterodyne receiver employing an automatic frequency-controlled oscillator such as that provided by my invention and showing the use of such oscillator in conjunction with an automatic or remote tuning device;

Fig. 2 is a diagrammatic illustration of a preferred form of the discriminator unit employed in the receiver of Fig. 1;

Fig. 3 is a diagrammatic illustration of one form of the automatic frequency-controlled oscillator unit provided by the invention, illustrating the phase-correction of the control tube used in cooperation with an electron coupled oscillator;

Fig. 4 is a similar illustration of another form of the oscillator unit wherein the quadrature voltage necessary for control is obtained from the oscillator grid circuit rather than from the output circuit of the electron coupled oscillator;

Fig. 5 is a diagrammatic illustration of a preferred form of the automatic frequency-controlled oscillator, employing a differential control circuit;

Fig. 6 is a similar illustration of an alternative form of the same type of oscillator unit;

Figs. 7 and 8 are diagrammatic illustrations of modifications of the automatic frequency-controlled oscillator containing certain refinements in the control circuit;

Figs. 9 and 10 illustrate certain operating characteristics of the control tubes of Figs. 3 to 8;

Fig. 11 is a graph showing the several types of operating characteristics which may be ob-

tained with several different control reactances; and

Figs. 12, 13 and 14 show the various different types of control reactances, those of Figs. 13 and 14 providing uniform control sensitivity in accordance with my invention.

The general operation of a superheterodyne radio receiver employing an automatic frequency-controlled oscillator may be understood by reference to the system of Fig. 1, wherein the incoming signal is amplified in a radio frequency amplifier, then supplied to a first detector in which it is heterodyned with a locally generated signal whose frequency is controlled, the heterodyne or intermediate frequency signal being then amplified in the subsequent I. F. amplifier. The I. F. signal is then demodulated in a second detector, and the demodulated or audio frequency signal is amplified and supplied to some utilization means, such as the conventional loud speaker L. S. The automatic control of the oscillator frequency is obtained by the use of two units, the first unit being a discriminator which forms a control or A. F. C. (automatic frequency control) signal, indicating the extent and the direction of the deviation of the intermediate frequency signal from the frequency to which the discriminator is turned, and the second unit comprising a controllable reactance for the frequency determining circuit of the oscillator whereby its frequency may be controlled over a certain range by this control or A. F. C. signal. As indicated in Fig. 1, a portion of the I. F. signal energy is supplied to the discriminator which supplies the A. F. C. signal to the frequency-controlled oscillator to control the locally generated signal applied to the first detector. The discriminator may also supply an A. V. C. (automatic volume control) signal to the parts of the system, as indicated. As shown in Fig. 1, the frequency-controlled oscillator may be employed in conjunction with an automatic or remote tuning device, as will be described hereinafter.

A suitable discriminator unit for use in connection with the present invention is shown in detail in Fig. 2. As noted above, I. F. signal energy preferably obtained from the output of the I. F. amplifier is supplied to the discriminator. This modulated intermediate frequency signal may be supplied to the control grid of the amplifier tube V₁ (Fig. 2) which tube may have a parallel resonant circuit 1 as its principal output load. Loosely inductively coupled to the resonant circuit 1 is a center-tapped resonant circuit 2, which is connected through diodes D₁ and D₂ to serially-connected loading-resistances R₁ and R₂ and to ground through blocking condensers C_{b1} and C_{b2}. These condensers are shunted by resistances R₃ and R₄, respectively, whose common connection may be connected to ground. The center tap of the inductance L of the resonant circuit 2 is connected to the common connection of the resistances R₁ and R₂, and is also connected to the anode of the amplifier tube V₁ through a blocking condenser C_{b3}. The anodes of the two diodes D₁ and D₂ are grounded for intermediate frequency signals by means of the condensers C_{b1} and C_{b2}.

The signals applied to the cathodes of the two diodes will include the signal across the output of tube V₁, which signal will build up between ground and the center tap of the inductance L across the resistances R₁ and R₂. For signals of the frequencies involved, the resistances R₁ and R₂ are effectively in shunt with each other. The

A. C. voltage induced in the inductance L will add vectorially to the A. C. voltage built up across the resistances R₁ and 2, and the phase relation between these two A. C. voltages will depend upon the frequency of the incoming signal. If the circuits 1 and 2 are tuned to the intermediate frequency, for signals of that frequency the A. C. voltage induced in L will be 90° out of phase with respect to the A. C. voltage across the shunt resistances R₁ and R₂. However, for frequencies other than the intermediate frequency, the vector relation between the A. C. voltage induced in L and the A. C. voltage across the resistances will differ by a phase angle greater than 90° or less than 90°, depending upon whether the frequency is higher or lower than the intermediate frequency. Thus, the scalar magnitude of the A. C. voltage between the anodes and cathodes of the two diodes D₁ and D₂ will depend upon the frequency of the incoming signal. If, for example, this signal were of lower frequency than that of the resonant frequency of the tuned circuits 1 and 2, the scalar magnitude of the signal applied to the diode D₁ might be greater than that of the signal applied to the diode D₂. On the other hand, if the incoming signal were of higher frequency than the said resonant frequency, the scalar signal magnitudes would be reversed.

Due to the rectifying action of the diodes D₁ and D₂, a direct current will flow from the anode to the cathode of diode D₁, through inductance L and back to the diode anode through the resistance R₁. The voltage applied to diode D₂ will likewise cause a direct current to flow from its anode to its cathode, through the inductance L and back to the diode anode through the resistance R₂. Thus, a D. C. potential will be built up across each of the resistances R₁ and R₂, and the magnitudes of these potentials will depend upon the scalar magnitudes of the voltages applied between the cathodes and anodes of the diodes D₁ and D₂. Where the incoming signal frequency is the same as the resonant frequency of the two tuned circuits 1 and 2, the voltage across R₁ will be equal in amplitude to that across R₂, and consequently, no current will flow through the series resistance R₃R₄ since the two ends of this resistance will be at the same potential. If, however, the incoming signal is of lower frequency than the resonant frequency of the tuned circuits 1 and 2, the potential across R₁ might be greater in amplitude than that across R₂, causing a current to flow through R₃ and R₄ and thus making the end of R₃ negative with respect to the end of R₄. If the common connection of these resistances is grounded, the potentials thereacross will be balanced with respect to ground, that is, as the one terminal becomes positive with respect to ground, the other will become negative by an equal amount. These rectified signal voltages may be filtered by the resistance-capacitance filters 3 and 4, so that across the output of the discriminator unit, there are obtained two control signal voltages balanced with respect to ground, the amplitudes and polarity of which will be determined by the departure of the I. F. signal frequency from the resonant frequency of the tuned circuits 1 and 2. These signal voltages constitute automatic frequency control voltages and may be used to control the frequency of a frequency-controlled oscillator, as described later. If the common connection of R₃ and R₄ is grounded as shown in Fig. 2, equal and opposite A. F. C. signals with respect to ground will be built up across R₃ and R₄. As will be explained

more fully hereinafter, the polarity of the A. F. C. signal suitable for use with the circuit of Fig. 4 is opposite that necessary for the circuit of Fig. 3. Thus in the one case the A. F. C. signal may be obtained from R_3 and in the other from R_4 . However, if only one A. F. C. signal is used, the whole signal across R_3 and R_4 may be employed by opening the ground connection to the junction of R_3 and R_4 and grounding the other end of the resistor. Thus, if the signal is obtained from R_3 , the end of R_4 connected to the diode D_2 may be grounded. Where two A. F. C. signals are employed, as in the differential circuit described hereinafter, then the junction of R_3 and R_4 should be grounded in order to obtain equal and opposite signals.

The particular diode connections shown in the discriminator of Fig. 2 offers certain advantages which are not obtained unless the cathodes are connected to the inductance L and the common connection of the resistances R_3 and R_4 is grounded. When these connections are used, the circuit is so arranged that leakage current paths through the cathode-heater connections to ground will not cause a change in the differential A. F. C. bias.

Suitable connections to energize the heaters from the filament winding of the power transformer are shown in Fig. 2. The same winding may be used to energize some or all of the other tubes in the receiver. However, to prevent large potential differences from building up between the cathode and heater winding and to minimize hum the center-tap of the filament winding should be grounded. If leakage current should flow between the heater and cathode the effect of such leakage in either diode is to place a small unidirectional voltage between the common connection of R_1R_2 and ground. This will cause equal currents to flow to ground through R_1R_3 and R_2R_4 , but will not cause a difference in potential across R_3R_4 and thus no A. F. C. bias when the differential circuit is used. This is not the case when the diodes are used in the reverse direction, when leakage in either diode will produce an extraneous potential in the discriminator circuit.

Since the anode of tube V_1 constitutes the point in the receiver at which the intermediate frequency signal is of greatest amplitude, an automatic volume control voltage may conveniently be obtained at this point by rectifying a portion of the output signal by means of the diode D_3 , whose cathode may be connected to the cathode of tube V_1 and whose anode may be connected to the anode of tube V_1 by means of a condenser C_{b4} . Since the I. F. signal amplitude at this point is very high, the diode anode may be biased back by a large negative "delay" voltage obtained from source 5 and thus a highly efficient source of automatic volume control voltage is obtained. This voltage may be filtered by a resistance-capacitance filter 6 and may be applied to the several preceding amplifier units to control the gain thereof, as indicated in Fig. 1.

In Fig. 3, there is illustrated one form of the frequency-controlled oscillator unit which may be employed in connection with the discriminator unit of Fig. 2. This oscillator unit comprises an oscillator tube V_2 , an oscillator tank circuit 7 including a variable condenser C_1 and an inductance L_1 in shunt therewith, and a control tube V_3 . The signal across the tank circuit is supplied to the control grid of the electron-coupled oscillator V_2 whose anode is connected back to the

5 tickler coil L_2 to provide the necessary feed-back. The cathode of the oscillator may be connected to ground through the self-biasing resistor-condenser combination 8 and the control grid may be biased by connecting it to ground through resistor 9. The output or oscillator signal which is supplied to the first detector may be obtained from the control grid, as shown. A signal voltage of the oscillator frequency but in phase quadrature with respect to the oscillator input signal voltage is obtained by means of the control reactance C , as described more fully later, and is applied via connection 10 to the grid of the control tube V_3 , thus causing the control tube to produce an output signal current in phase quadrature with respect to the input signal voltage of the oscillator, which, of course, is in phase with respect to the signal voltage between the anode and cathode of the control tube. Thus, the output current and output voltage of the control tube are in phase quadrature with respect to each other, and their relative magnitudes will depend upon the mutual conductance of the tube and the magnitude of the input signal. Therefore, neglecting for the moment the effect of the in-phase signal component discussed hereinafter, the control tube will appear as a reactance whose magnitude is determined in part by the mutual conductance of the tube, which in turn is determined by the bias applied to the control grid of the tube, the mutual conductance being greater when the grid is less negative. Hence, the magnitude of the reactance presented by the control tube will be determined by the bias upon the grid of the tube, and by applying the A. F. C. voltage obtained from the discriminator as a bias, the tube may be utilized to control the resonant frequency of the oscillator tank circuit in such manner that if the intermediate frequency signal of the receiver is less than the resonant frequency of the tuned circuits 1 and 2, the resonant frequency of the oscillator is increased, to thus increase the heterodyne signal frequency and to bring the receiver more nearly into tune. It will be noted that the degree of control is determined by the degree of mistuning and thus the type of control action here involved is that known as a "servo" action. By utilizing a sensitive control, the receiver can be brought to very nearly perfect tuning, but never to exactly perfect tuning. The slight misalignment, however, is not sufficient to impair the operation of the receiver.

It will be seen that the device of Fig. 3 requires the application thereto of only one A. F. C. bias voltage which may be obtained from the device of Fig. 2 as above indicated.

In the adaptation of such an automatic frequency-controlled oscillator to a practical receiver, it was found that this control tube presented an appreciable undesirable resistance to the tank circuit, which resistance, if it did not overload the oscillator until the latter ceased to function, varied with both frequency and A. F. C. bias thus causing undesirable changes in the amplitude of signal supplied to the first detector. This undesired resistance is due principally to three sources described hereinafter. Following the practice of the invention, this resistance may be either balanced out identically or modified to a value independent of both frequency and A. F. C. bias and such as not to affect the oscillator performance adversely, by introducing a direct-phase signal component in the control tube input circuit, which component causes the control

tube to appear as a resistance of opposing polarity as compared with the undesired resistance.

The three general sources of undesired resistance are: one, the undesired in phase signal due to the control tube grid-to-anode inter-electrode capacity; two, the anode-to-cathode A. C. resistance of the control tube, and three, the direct phase signal component in the signal obtained from the control reactance.

Considering each of these sources in more detail, it was found first that due to the inherent capacity between the control grid and plate of the control tube V_3 , indicated by the dotted condenser C_{sp} in Fig. 3, the control tube tends to present an appreciable resistance to the tank circuit. This may be seen from a consideration of the voltage relations in the input circuit of the control tube. As will be shown later, the control reactance, which comprises the condenser C of Fig. 3, should preferably be a capacitive reactance, although not necessarily a condenser. Therefore, the control grid of the control tube V_3 is capacitively connected to ground by means of the control reactance, and is capacitively coupled to the anode by means of the inherent grid-to-anode capacity of the control tube and the external wiring. Consequently, a change in anode voltage will cause a proportional change in voltage of the control grid, which in turn will cause a variation in the space current of the tube. Thus, this coupling introduces an undesired in-phase input signal. As an increase in anode voltage will cause an increase in anode current, the tube acts as a resistance and will absorb energy from the tank circuit. If, on the other hand, the control reactance were inductive, the resistance of the control tube would be negative and it would cause the control tube to oscillate, but at a frequency other than that desired. In fact, in general, the frequency may shift back and forth between that determined by the oscillator proper and that at which the control tube tends to oscillate, and the result is a signal generally useless for the present purpose.

A second source of resistance is the actual anode-to-cathode effective A. C. resistance of the control tube itself. Thus, independently of the grid potential, if the anode voltage is varied, the anode current will vary in such a way as to cause absorption of energy by the control tube. In vacuum tubes of the type generally suited for this purpose, the amplification factor is substantially constant and thus this second resistance will vary inversely with the mutual conductance of the tube, i. e. with A. F. C. bias.

The third source of resistance is due to an undesired in-phase signal component in the signal obtained from the control reactance and supplied to the input circuit of the control tube. While the cause of this in-phase component is not completely understood, it may be said that in part at least it is due to the oscillator grid leak. In part it may be due to capacitive coupling or coupling of other nature in the oscillator itself. Still another source might be the resistance through which energy may be supplied to the output anode of the oscillator. In any event an undesired direct phase signal component may be present.

As described above, an input signal in phase with the signal in the control tube output will cause the tube to appear as a positive resistance and absorb energy while an input signal in phase opposition will cause the tube to appear as a negative resistance. Following the practice of the invention, the undesired effective resistance component of the control tube output circuit may

be considered in terms of the equivalent direct-phase input signal which would cause such a resistance if the tube were replaced by an ideal amplifier. For practical purposes it matters not whether such equivalent signal is actually present in the circuit or is simply assumed to be there. In either event the deleterious effect of the undesired resistance may be eliminated by supplying to the input circuit a direct phase signal of opposing phase relation with respect to the phase of the undesired equivalent signal. Thus, briefly, an ideal amplifier supplied with an input signal in phase quadrature relation with its output signal is desired to form a pure reactance. Due to physical limitations of available apparatus, however, the impedance of the control tube will contain an undesired resistive component due physically at least in part, and hypothetically entirely, to an undesired direct phase signal component in the input circuit. By the invention, a phase-correcting direct phase input signal is provided which opposes the undesired signal component, thus eliminating the deleterious effects caused by it.

In general, the equivalent undesired signal will be in-phase with the control tube output circuit voltage. It is likewise independent of A. F. C. bias and will vary with frequency only if the effective capacitance of the control reactance varies with frequency. Assuming, however, that the undesired signal is independent of both frequency and A. F. C. bias, the effect of the resistive component in the control tube output on the resonating circuit will vary with both of these factors. A suitable direct phase voltage in phase opposition to the undesired signal may be obtained, following the practice of the invention, by connecting an adjustable condenser C_2 of proper capacity between the control grid of the control tube and the anode end of the tickler coil L_2 . As the voltage at the anode end of the tickler coil L_2 is 180° out of phase with that supplied to the anode of the control tube V_3 , and as this point is capacitively coupled to the grid by the condenser C_2 , it will supply an input signal in-phase with the voltage across the tickler coil L_2 and thus 180° out of phase with the plate voltage of the control tube V_3 and 180° out of phase with the undesired input voltage and dependent upon the control reactance in the same way. By properly proportioning the capacity of C_2 , the voltage provided by the phase-correcting circuit may be made equal in magnitude to the undesired signal and as it is opposite in phase, the two will oppose each other, leaving only the quadrature component.

Preferably the undesired in-phase signal component is opposed by an equal and opposite signal obtained as above described. In certain instances, however, an alternative method of obtaining this opposing signal may be employed. This latter method consists in modifying the control reactance so that it will include a resistive component. In Fig. 3, there is shown a small resistance r serially connected to the condenser C . The magnitude of this resistance will be small as compared with the impedance of C . Thus, the undesired signal due to the inter-electrode capacity and the control reactance will be uniform over the band and proportional to the control tube grid-to-plate inter-electrode capacity divided by the capacitance C . The equivalent undesired direct phase signal due to the other two sources may likewise in many instances be uniform over the band. Now the control reactance circuit is substantially a constant

current circuit and thus the voltage due to the series resistance will be substantially a constant over the band, and as it will be in phase opposition to the undesired signal in the input circuit of the control tube due to the 180° phase shift between input and output signals of V_2 , this signal due to the resistive component of the control reactance is a proper signal to provide the desired phase correction. It will be noted that the resistance r is adjustable and that the resistance supplying energy to the output anode of V_2 is sufficiently large to be negligible compared with the low impedance control reactance in shunt with it.

While two means of obtaining the voltage in phase opposition to the undesired in-phase signal have been shown in Fig. 3, it will be understood that either or both may be employed depending upon the particular circumstances. In either case, when the control tube is phase-corrected in accordance with my invention, the voltage between its anode and ground is in true phase quadrature with the voltage supplied by the control reactance to the grid.

It will be noted that in Fig. 3 the signal supplied to the control tube is obtained from the output circuit of an electron coupled oscillator. As is known, in tubes of this type, the space current to the output anode is determined largely by the voltage of the oscillator grid and is substantially independent of the voltage of the oscillator anode. Thus, by providing a reactive output circuit or control reactance, the desired quadrature voltage may be obtained thereacross, as described more fully hereinafter, and supplied to the control grid of the control tube. The gain of the control tube and thus its effective reactance may be controlled by the A. F. C. bias as indicated.

In Fig. 4 there is shown an alternative method by which a voltage in quadrature phase relation with respect to the oscillator grid voltage may be obtained. In this case, the oscillator grid is connected to the control reactance C' by a large resistance R and an inductance L' . Preferably the inductance L' and control reactance C' should be tuned to be resonant in the middle of the band over which the oscillator may be tuned, and the resistance of R should be considerably greater than the impedance of C' or L' . Under these conditions, the signal across the control reactance C' will be exactly in phase quadrature with that across the output circuit of the control tube V_2 for the resonant frequency of $L'C'$ and substantially so over the rest of the band. Thus the signal across the control reactance C' constitutes a proper signal to be applied to the control grid of the control tube. It will be noted, however, that this voltage is 180° out of phase with respect to the equivalent voltage obtained in Fig. 3 and hence the polarity of the A. F. C. bias should be reversed to obtain the same direction of control in the two cases. In other words, in Fig. 3 an increase in A. F. C. bias will cause a change of oscillator frequency in the same direction as that caused by a decrease in A. F. C. bias in the circuit of Fig. 4. The discriminator of Fig. 2 provides either signal. The phase correction may, however, be obtained in exactly the same manner in the two cases, that is by the use of the variable condenser C_2 . Where it is desired to obtain phase correction by means of a resistive component in the control reactance, this may be done by inserting a small resistance (corresponding to r of Fig. 3) in series

with C' so that it is included in circuit between connection 10 and ground. In order to obtain a proper phase relation for the correcting signal, the anode of V_3 may be connected to the anode end of L_2 instead of the grid end of L_1 .

In Fig. 5, there is illustrated a preferred form of the frequency-controlled oscillator unit which is preferably employed with the discriminator unit of Fig. 2. In this instance, the cathode of the oscillator V_2 is connected to ground through a self-biasing resistance-capacitance filter and the control grid is biased by tapping in on the resistance of this filter. This preferred oscillator unit employs a phase-corrected control circuit which has certain important advantages, as will be pointed out more particularly hereinafter. In this instance, two control triodes in the form of a double triode tube V_4 are used and are so coupled into the tank circuit that the effect of one is in the opposite direction to the effect of the other. Thus, for example, an increase in bias on one triode might cause an increase in oscillator frequency, whereas an increase in bias on the other triode would cause a decrease in oscillator frequency. Therefore, in this instance two A. F. C. control voltages are used, one of which increases when the other decreases, and thus when the bias on one triode increases the bias on the other triode will decrease, and vice versa. By using a discriminator unit of the type shown in Fig. 2, the desired control voltages may be obtained.

The circuit of Fig. 5 is generally similar to that of Fig. 3 insofar as the method of obtaining the quadrature voltage is concerned. It will be noted, however, that the same quadrature signal is applied to each control grid of the triodes of tube V_4 . In this differential circuit, the grid-to-plate inter-electrode capacitance of each triode acts as the phase-correcting capacitance for the other triode and thus the use of a phase correcting resistive component in the control reactance is unnecessary. The control reactance C is connected between the grids and ground as before. If the respective anode inductances of the two triodes are equal and if the respective inter-electrode capacitances are equal, as would be the case for a double triode or identical tubes, then no signal appearing between the anodes of the two triodes can cause a signal to appear in the input circuits of the triodes due to the inter-electrode capacitances of the triodes, and thus the triodes will appear as pure reactances due to the quadrature voltage applied to their respective grids. In case the inter-electrode capacities of the triodes should differ for some reason, the lesser capacity can be increased by the use of a small phasing condenser analogous to the use of such a condenser shown in Fig. 3.

The deleterious effect of the resistive component of the control tube reactance which is due to the second source, that is to the anode-to-cathode resistance of the control tubes, need not, in general, be opposed where two control tubes are used since under these conditions this resistive component does not vary with frequency or with A. F. C. bias and thus may be overcome by increasing the feed back from the oscillator. It will be noted that the resistance component of each tube will be in shunt with each other and with the resonating circuit. Each resistance will vary with A. F. C. bias but not with frequency. However, as the A. F. C. bias is varied it will cause the resistance of one tube to increase, while that of the other decreases. Thus the two variations oppose each

other and except for second order effects the resultant resistive component due to the two will be unchanged.

In the operation of this device, a signal voltage of the oscillator frequency, but in phase quadrature with the oscillator input signal voltage, is applied to the grids of the two triodes of tube V₄, thus causing each triode to produce an output signal current in phase quadrature with respect to the input signal voltage of the oscillator, which, of course, is in phase with respect to the signal voltage between the anode and cathode of one triode and 180° out of phase with respect to the signal voltage between the anode and cathode of the other triode. Thus it will be seen that the output current and output voltage of each triode are in phase quadrature with respect to each other, and the magnitudes of these signals will depend upon the mutual conductance of the triodes and the magnitude of the input signal. Therefore, each triode will appear as a reactance (one positive and one negative) whose magnitude is determined in part by the mutual conductance of the triode. The mutual conductance of the triode, however, is determined by the bias applied to its control grid, being greater when the grid is less negative and, therefore, the magnitude of the reactance presented by the triodes will be determined by the bias upon their grids, and by applying the A. F. C. voltage as a bias, the triodes may be utilized to control the resonant frequency of the tank circuit in such a way that if the intermediate frequency signal of the receiver were less than the resonant frequency of the tuned circuits 1 and 2, then the resonant frequency of the oscillator would be increased, which would tend to increase the heterodyne signal and thus bring the receiver more nearly into tune, and vice versa.

In Fig. 6, two separate control tubes V₅ and V₆ are used and are connected in the manner of the triodes of Fig. 5. The oscillator proper is shown as comprising two tubes V₇ and V₈, one a triode and the other a multi-element tube of the electron mixer type. By connecting the input grids of these two tubes together and using only the anode of the triode as the oscillator anode, a more powerful oscillator may be obtained and the second control grid of the electron coupled oscillator is left free for other purposes, such as described below. It will be understood that other types of oscillators may be used, such as those shown in the other illustrations. The quadrature signal may be obtained across a control reactance C connected to the output of V₈.

Suitable control signals for this purpose may be obtained in several different ways. In some cases, it is desirable that the A. F. I. circuit of the receiver be inoperative while the receiver is being tuned but operative after the tuning operation is effected. This may be accomplished by providing a switch of the push-button type or an inertia switch mechanically operated by movement of the tuning condenser shaft so that when the set is being tuned the switch supplies a negative bias to the second control grid of the tube V₈, thus biasing out the quadrature signal, while, when the push-button is released or when the movement of the tuning condenser shaft is completed, the switch opens returning the control grid bias to normal and thus rendering the A. F. C. circuit 70 operative.

Similar useful results may be obtained by the electrical circuit shown in Fig. 6. In this circuit, two diodes D₄ and D₅ and a resistance R₇ are used to supply the bias for the second grid of V₈. The 75

anodes of the diodes are connected together and to ground through the resistance R₇. The cathodes of the diodes are connected to the two A. F. C. leads. The second grid is connected to the diode anodes. When one of the A. F. C. leads is negative with respect to ground, current will flow through the diode connected to that lead and thence to ground, causing negative bias to build up across R₇ proportional to the negative A. F. C. bias. No current will flow through the other diode as its cathode is positive with respect to its anode. Thus the bias supplied to the second grid of V₈ will be proportional to the voltage of whichever A. F. C. lead is negative. This bias when applied to V₈ will decrease the frequency control sensitivity of the circuit when the receiver is badly mistuned but will not affect the operation when the receiver has been approximately tuned. Thus it is possible to tune the receiver manually without having the A. F. C. circuit lock in on a strong station and drag this station through many channels before releasing it. The receiver is thus enabled to receive some other station. The cathodes of the two control tubes are connected to ground through blocking condensers C₆₅ and C₆₆ and through a self-biasing network so arranged that the D. C. potential of the cathode of tube V₅ may be slightly modified with respect to that of tube V₆ by variation of the point at which the potentiometer P is grounded. In this manner, slight variations in the mutual conductance of the two tubes may be equalized. It is, of course, desirable that the two tubes have identical electrical characteristics.

Aside from the above noted differences, the device of Fig. 6 is similar to that of Fig. 5 and operates in the same manner.

In Figs. 7 and 8 are shown two further refinements which while not essential to the attainment of commercially satisfactory results, may be used to advantage in certain instances. In Fig. 7 a triode V₉ is used in cooperation with the resonant circuit 7 to form a source of oscillations. In this figure L₄ L₆ L₈ L₉ may be separate inductances closely inductively coupled to each other instead of two inductances as before. This expedient may be used in any of the above circuits. A signal may be obtained from the output circuit of V₉ and applied to a gain control tube V₁₁ which may contain the control reactance X₃ in its output circuit. While shown as a condenser any of the control reactances described herein-after may be used here. A quadrature signal is obtained from the control reactance and applied to the control tube V₁₀. The phase correcting signal may be obtained by means of the adjustable condenser C₂ from the inductance L₄. If desired C₂ might be connected to L₆ or an adjustable resistance in the control reactance circuit may be used. Both of these methods have been described in connection with Fig. 3.

It will be noted that in Fig. 7 the controllable reactance is the output of control tube V₁₀ while the magnitude of the reactance is controlled in the gain control tube V₁₁. In the specification and claims, by control tube is meant that tube which is connected to supply signal to the frequency determining circuit of the oscillator and thus forms the control reactance. In the other figures the control tube has also been used to act as the gain control but this function may be accomplished in a separate tube such as V₁₁ in Fig. 7, which tends to minimize further any variations in generated signal amplitude with A. F. C. bias.

In Fig. 8 is shown a differential circuit in which the input circuits are supplied with separate quadrature signals in phase opposition while the output circuits are in shunt with each other. The oscillator part of the circuit is similar to that of Fig. 5. It will be noted, however, that the anodes of control tubes V_{12} and V_{13} are connected together and to L_1 of resonant circuit 7. The control reactance comprises the inductance L_3 , condenser C and resistance r . The inductances L_6 and L_7 may be equal and closely coupled and thus the signal across L_7 will be equal and opposite that across L_6 . The impedance of L_6 may be considerably greater than that of C , in which case the reactance of the unit will be substantially that of the condenser. A quadrature signal will develop across L_6 and an equal and opposite signal across L_7 . These two out-of-phase signals are applied to the grids of V_{12} and V_{13} . Equal and opposite A. F. C. biases may likewise be applied to these grids and the differential reactance obtained in the combined output circuits. As before the undesired direct-phase signal due to the inter-electrode capacity of the one control tube opposes that of the other.

While the undesired resistance due to the anode-to-cathode resistance of the control tube and due to the direct phase component of the quadrature signal will to a certain extent remain constant independent of A. F. C. bias as before, this component may be opposed by an adjustable resistance r in the control reactance. This resistance may be small and there will be built up across it a small direct phase component which is applied in like phase to the grids of each tube. In the circuit as shown, an increase in output voltage of V_{12} and V_{13} will cause a decrease in grid voltage of each tube and thus r may be used to introduce a signal to oppose an effective energy absorbing resistance, in the resonant circuit. By connecting the anodes of the control tubes to L_2 instead of L_1 a phase correcting signal of opposite polarity is obtained. Thus by the circuit of Fig. 8 the undesired resistive component of the impedance of the control tubes may be eliminated completely as compared with the circuits of Figs. 5 and 6, in which its effect is reduced to a small constant value.

The use of a differential circuit, such as shown in Figs. 5, 6 and 8, offers certain other important advantages. This may be seen from a consideration of Figs. 9 and 10. Fig. 9 depicts the action of an oscillator unit employing one control tube, such as shown in Figs. 3, 4 and 7, while Fig. 10 depicts the action of an oscillator unit employing differential tubes, such as shown in Figs. 5, 6 and 8. In Fig. 9, there is shown a curve in which the ordinate represents the departure of the oscillator frequency from the frequency which the oscillator would have in the absence of the control tube. It will be seen that this frequency deviation is proportional to the mutual conductance of the tube and thus, by representing the abscissa as the grid bias and drawing a conventional mutual conductance characteristic for the control tube, a curve is obtained in which the frequency departure is plotted against the A. F. C. bias. In Fig. 9, the natural frequency of the oscillator tank circuit may be represented by F_2 . Due to the addition of the control tube, however, the mean frequency about which the oscillator frequency is deviated should be about half the total possible frequency deviation and this is represented by the point F_0 . The grid of the control tube would then be normally biased

by the amount indicated so that the zero-controlled oscillator frequency for any particular manual adjustment of the tank circuit would correspond with F_0 . Then a positive or negative change in the A. F. C. bias about the zero point indicated by the dotted line would cause the oscillator frequency to shift about the frequency F_0 . If, however, the mutual conductance of the tube were to change for any reason, for example, due to a change in the plate voltage or the cathode temperature, or due to aging of the tube itself, the mutual conductance curve will change, say to a position shown by the broken-line. Consequently, the mean frequency about which the oscillator frequency is varied will shift to a position F_1 . However, the remaining elements of the receiver including the tank circuit, R. F. circuits, etc., will have been adjusted so that the receiver is properly aligned when the oscillator frequency changes about the value F_0 , and if for any reason this mean frequency were shifted to the position F_1 , then the alignment of the receiver would be upset and the other circuits of the receiver would not be properly oriented with respect to the oscillator. Using the nomenclature of the art, the receiver would not "track" and the dial calibration would be upset.

These difficulties are alleviated by the use of the differential circuit whose operating characteristic is shown in Fig. 10. In this circuit, one control tube is adjusted to cause a change of frequency in one direction, while the other control tube is arranged to cause a frequency change in the opposite direction. Therefore, the change in tuning due to one tube may be indicated by the characteristic A similar to that of Fig. 9, while the change in tuning due to the other tube is represented by a curve B sloping in the opposite direction, since the A. F. C. biases supplied to the two tubes are equal and opposite, and thus when the grid of one tube becomes positive, that of the other tube becomes negative with respect to the normal bias. The actual change in frequency will be determined by the difference between the two and this is indicated by the resultant curve D. The coordinates of the graph in Fig. 10 are the same as those of Fig. 9. It will be observed that in this instance the actual frequency of the oscillator for one value of bias will be the same as that of the tank circuit in the absence of the control tubes, and this value of bias, which will occur when the two tubes are biased at the same point irrespective of the potential of that point, is selected as the mean frequency about which the oscillator is to vary. If now, the mutual conductance of each tube changes by the same amount, then there will be no change whatsoever in the mean frequency. Due to the differential nature of the circuit, variations in the mutual conductance of the control tubes which do occur, will be substantially the same for each tube. For example, since the filaments of the tubes may be connected together and since the same plate voltage is applied to each tube, changes in these parameters would cause substantially identical changes in the mutual conductance of the tubes. Furthermore, it is advantageous to use for the control tubes a tube having two triode sections in the same envelope, which provides that the two triodes will age at the same rate. It will further be apparent that any hum picked up by the plate leads or grid leads of the tubes will cause equal changes in the equivalent mutual conductance of the

tubes, and, therefore, the differential circuit is free of frequency modulation due to these sources. Furthermore, the automatic frequency control feature may be removed by simply short-circuiting the A. F. C. voltage, for example, by means of the switch S shown in Fig. 2, without causing any misalignment of the receiver.

The normal bias for the two control tubes may conveniently be obtained by means of a common resistance in the cathode circuits of the control tubes. This resistance may be connected to ground and serves to establish a normal negative bias common to both control tubes. It will be noted that the center point of the resistances R_3 and R_4 across which the A. F. C. voltages are formed is likely grounded and thus the A. F. C. voltages will bias the grids of the control tubes positive or negative with respect to this normal bias. Due to the differential nature of the circuit, the normal bias point will be substantially independent of the A. F. C. biases. On the other hand, were a single tube used, it would be necessary to provide some external source of a normal bias or alternatively operate the control tube self-biased and increase the sensitivity of the discriminator unit to overcome the variation in self-bias with variations in A. F. C. bias.

It will further be noted that due to the differential feature of the control, the control sensitivity is made substantially uniform or linear about the mean frequency. This then, provides a convenient way of obtaining frequency modulation. In other words, while in the present instance, it is desired that the oscillator should be completely unmodulated, and provide a substantially pure sinusoidal signal, in the event that it was desirable to frequency-modulate the oscillator for use in some other circuit, this could be accomplished conveniently by supplying the modulating signal to the control grids of the two control tubes by an input circuit balanced to ground, and linear frequency modulation would be obtained. It will further be apparent that any degenerative effects due to the self-biasing resistor and filter in the cathode circuit of the two triodes will be balanced out by the circuit of the invention, and consequently, variations in the cathode voltage with respect to ground will not cause variations in the frequency of the output signal. Additionally, it will be observed that as the tubes age and the mutual conductance decreases, the only change in the operation of the circuit will be a slight change in its sensitivity as shown by the broken-lines in Fig. 10.

Contrasted with the above advantages of the differential control circuit, the control circuit employing a single control tube, as shown in Figs. 3 and 4 has the advantage that it requires fewer parts and is less expensive to manufacture.

Regarding the invention generally, an important feature is the provision of the resonant control reactance mentioned above. In the circuits of Figs. 3, 4, 5, 6 and 7, it will be noted that the voltage in quadrature with the oscillator grid voltage is obtained by means of a control reactance comprising a condenser C. This voltage will cause the control tube to appear as a negative inductance, since the impedance of the control tube is proportional to the negative reciprocal of the control reactance multiplied by the mutual conductance of the control tube and by the mutual conductance between the control grid and the output anode

5 of the electron-coupled oscillator. This inductance is inserted in shunt with the inductance of the resonant circuit. However, in tuning the resonant circuit, the capacitance is generally varied, and, therefore, the sensitivity of the control unit will be proportional to the ratio of the inserted equivalent inductance and the natural inductance of the tank circuit. The sensitivity therefore, will be proportional to the frequency, since a given percentage change in inductance will cause a proportional percentage change in frequency, regardless of the resonant frequency of the circuit. This is shown in Fig. 11, which is a graph in which the ordinate is control 15 sensitivity in terms of k. c. frequency shift per volt of A. F. C. bias, and the abscissa represents the frequency to which the tank circuit is manually tuned. The control sensitivity, which in this instance is proportional to the oscillator frequency, is represented by the curve I.

If, however, the control reactance were an inductance, such as shown at X in Fig. 12, then the reactance presented by the control tube would be a negative capacity which would effectively be in 25 shunt with the physical condenser in the tank circuit. However, since the frequency of the tank circuit is manually adjusted by varying the capacity of the tuning condenser, and since this change is proportional to the square of the frequency, the control sensitivity will then vary as the cube of the frequency and will be in the opposite direction from that previously noted. This condition is shown by curve II in Fig. 11.

It is desirable, however, that the control sensitivity be substantially uniform over the frequency band in which the oscillator may be tuned, which band may extend over a frequency range of about 2 to 1. To achieve this result, a capacitive reactance which reflects back as an inductance is preferably employed. To make the control uniform, the effective inductance should vary inversely with frequency and thus a capacitive reactance is required which is inversely proportional to frequency squared. As the quadrature voltage supplied to the control tube is proportional to the control reactance, the reactance desired should have the characteristic that the product of the voltage thereacross multiplied by the frequency squared is substantially constant over the band. This condition obtains when a resonant control reactance is used.

In Fig. 13, for example, there is shown a control reactance comprising a series-tuned circuit X_1 , which circuit is resonant above the frequency band of the oscillator. The circuit will then appear as a capacitance, but the control reactance when transformed by the control tube will appear as a negative inductance which, over the oscillator frequency range, will vary practically inversely with frequency. The control sensitivity will then be substantially uniform over the band. This condition is shown by the curve III of Fig. 11. Taking a specific example, if it is desired to vary the oscillator frequency over the necessary (1.0 to 2.0 m. c.) range for a superheterodyne receiver adapted to receive signals in the standard broadcast band, the control reactance should be tuned to be resonant at about 2.65 megacycles, and under these circumstances, the sensitivity at the ends of the band which represent the minimum sensitivity, will be 84% of the maximum sensitivity which will occur at about 1½ megacycles.

The preferred form of the control reactance is shown in Fig. 14 and constitutes a parallel resonant circuit X_2 tuned below the frequency band

and which over the operating range will then appear as a capacitive reactance. In the particular case above cited, the circuit should be tuned to be resonant at about .75 megacycle and under these circumstances, the minimum control sensitivity within the band will be 84% of that at the extreme ends of the band, which represents the maximum sensitivity. The characteristic for this reactance is shown by curve IV in Fig. 11.

It will be understood that Figs. 12 to 14 are fragmentary views showing different forms of the control reactance which may be used in the controlled oscillator.

The parallel resonant circuit has the advantage that the output anode to ground inter-electrode capacity of the oscillator tube is in shunt with that of the condenser in the resonant circuit and thus combines with the latter condenser without disturbing the desired properties of the circuit, whereas in the series circuit, it is effectively in shunt with the whole control reactance. The parallel inductance likewise provides an easier way of supplying energy to the anode, doing away with the resistor used in the series circuit.

Where the resonant circuit of Fig. 13 or Fig. 14 is used with the single control tube of Fig. 3 or Fig. 4 and where it is desired to provide phase correction by means of a resistive component in the control reactance it will, in general, be necessary to provide a plurality of resistances particularly if the oscillator frequency is to be varied over a wide range. As will be apparent, the undesired in-phase signal will depend upon the ratio of the reactive part of the control reactance to the impedance of the grid-to-plate inter-electrode capacitance of the control tube. It is then necessary to provide a control reactance whose conductance varies with frequency substantially similarly to the variations with frequency of this ratio. In general, satisfactory phase correction may be obtained by the use of two properly proportioned resistors one in shunt and one in series in the resonant control reactance. It will be apparent that more complicated networks may be used to obtain the desired quadrature and in-phase signals.

Referring again to Fig. 1, the tuning means of the R. F. amplifier, 1st detector and oscillator, for example, the main tuning condenser in each unit, may be ganged and automatically and remotely controlled by a suitable tuning mechanism, as indicated by the broken-line representation. As such devices are well known in the art, further description of them is unnecessary except to point out that in general such devices include a switch for rendering the output circuit of the receiver inoperative while the tuning of the receiver takes place. When such devices are used with a receiver employing automatic frequency control, it is desirable that the A. F. C. bias be reduced to zero at least momentarily after the positioning of the tuning means is accomplished so that when the A. F. C. again becomes operative, it will lock in on the intended station and not on a neighboring channel. An important feature of the invention is the provision of electrical means by which this may be accomplished using the simple mechanical structure of the prior art. As will be apparent, the important point is to prevent the A. F. C. bias from building up until after the receiver is completely tuned and the tuning condenser movement has ceased, whereas the switch for rendering the receiver inoperative is usually so arranged that it re-establishes transmission as the

tuning operation is being completed, but before the tuning condenser has finally come to rest. Following the practice of my invention, the resistance-capacitance filters 3 and 4 of Fig. 2 are arranged to have a long time-constant and a switch S_1 mechanically operated by the tuning means, as indicated in Fig. 2, is provided by which the condensers of the filter may be shunted and thus discharged. When the switch S is closed, the voltage across the filter condensers and thus the A. F. C. bias is reduced to zero. When the switch S is opened, there will be no voltage across the condensers and thus electrically the A. F. C. bias will remain zero until sufficient time has elapsed to permit a charge to build up on the condensers. The time interval between the time the switch S opens and the time when the A. F. C. bias becomes operative will depend upon the time constant of the filter condensers and may be several seconds. Preferably, it should be sufficiently great to permit the tuning condenser to come completely to rest. Thus when the A. F. C. circuit locks in on the nearest station, it will be the desired station and not one on an adjacent channel. If desired, the time constant of the filters may be further augmented by the use of an additional condenser C_f in shunt therewith. The switch S_1 may be similar to the prior art switches used in such tuning devices to render the receiver output inoperative. A preferred form of such an automatic tuning means is shown in the copending application of Leo B. Glaser et al., Serial No. 94,674, filed August 6, 1936.

For purposes of this specification and claims, "quadrature" is defined as the phase relation between two vectors which are substantially perpendicular to each other, and thus the phase relation between two signals differing in phase by approximately 90° to 270° . "Direct" phase relation is defined as the phase relations between two vectors which are substantially co-linear with each other and thus the phase relation between two signals differing in phase by approximately 0° or 180° .

It will be seen from the illustrated embodiments and the above description that in each case the frequency-controlled unit comprises a loop circuit which includes the oscillator circuit, a thermionic device for transferring the signal in the loop circuit, means in the loop circuit for forming the quadrature voltage, and means for applying such voltage to the tank circuit. While the illustrated embodiments represent the most practical methods using commercially available tubes, the invention contemplates broadly the use of a loop circuit of the character above mentioned embodying suitable means therein for providing the desired quadrature voltage.

While certain forms of the invention have been illustrated and described for the purpose of disclosure, it will be understood, of course, that the invention is not thus limited but is capable of various modifications other than those illustrated. Any such modifications are deemed to be within the scope of the invention.

I claim:

1. In an electrical system for forming frequency-controlled oscillations, means for generating self-sustained oscillations comprising a space discharge device and an associated resonant circuit including reactive elements, a control space discharge device having an input circuit and an output circuit, means for coupling said output circuit in operative relation with at

least a portion of a reactance of said resonant circuit, means for obtaining a voltage in phase quadrature relation with the voltage across said output circuit and for applying said voltage to said input circuit, the reactance of said output circuit containing an undesired resistive component caused by the aforesaid elements, and means for obtaining a voltage substantially in direct phase relation with said output circuit voltage and for applying said obtained voltage in said input circuit for reducing the effect of said undesired resistive component.

2. In an electrical system for forming frequency-controlled oscillations, means for generating self-sustained oscillations comprising a space discharge device and an associated resonant circuit including reactive elements tunable over a band of frequencies, a control space discharge device having an input circuit and an output circuit, means for coupling said output circuit in operative relation with at least a portion of a reactance of said resonant circuit, an impedance including a resistance, an inductive reactance and a capacitive reactance, said reactances being resonant at a frequency in the middle of said band, said impedance being energized by a signal derived from said resonant circuit, and means for obtaining a signal substantially in phase quadrature relation with the signal across said output circuit from one of said reactances and for applying said obtained signal to said input circuit, said resistance and said reactances being so related as to reduce the transfer of a direct phase signal to said input circuit.

3. In an electrical system for forming frequency-controlled oscillations, means for generating self-sustained oscillations comprising a space discharge device and an associated resonant circuit including reactive elements, a control space discharge device having an input circuit and an output circuit, means for coupling said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, and means including a capacitive element for obtaining a voltage substantially in phase opposition to said undesired voltage and for applying said last-named voltage to said input circuit.

4. In an electrical system for forming frequency-controlled oscillations, means for generating self-sustained oscillations comprising a space discharge device and an associated resonant circuit including reactive elements, a control space discharge device having an input circuit and an output circuit, connections between said output circuit and said resonant circuit for connecting said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, and means including a capacitive element associated with said resonant circuit for

obtaining a voltage substantially in phase opposition to said undesired voltage and for applying said last-named voltage to said input circuit.

5. In an electrical system for forming frequency-controlled oscillations, means for generating self-sustained oscillations comprising a space discharge device and an associated resonant circuit including reactive elements, a control space discharge device having an input circuit and an output circuit, means for coupling said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, a second control space discharge device coupled to said resonant circuit and having input and output circuits with inherent capacitive coupling therebetween, and means utilizing the inherent capacitive coupling between the input and output circuits of said second control space discharge device, for obtaining a voltage substantially in phase opposition to said undesired voltage and for applying said last-named voltage to the input circuit of said first control space discharge device.

6. In an electrical system for forming frequency-controlled oscillations, means for generating self-sustained oscillations comprising a space discharge device and an associated resonant circuit including reactive elements, a control space discharge device having an input circuit and an output circuit, means for coupling said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, a second control space discharge device coupled to said resonant circuit and having input and output circuits with inherent capacitive coupling therebetween, and means utilizing the inherent capacitive coupling between the input and output circuits of said second control space discharge device, for obtaining a voltage substantially in phase opposition to said undesired voltage and for applying said last-named voltage to the input circuit of said first control space discharge device, the input and output circuits of said second control device being coupled respectively to the input and output circuits of said first control device, the signal introduced in said resonant circuit by one of said control devices being opposite in phase with respect to the signal introduced by the other control device.

7. In an electrical system for forming frequency-controlled oscillations, means for generating self-sustained oscillations comprising a space discharge device and an associated resonant circuit including reactive elements, a control space discharge device having an input circuit and an output circuit, means for coupling said output circuit in operative relation with at least a portion of a reactance of said resonant circuit, means for obtaining a signal voltage in

phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, a second control space discharge device coupled to said resonant circuit and having input and output circuits with inherent capacitive coupling therebetween, and means utilizing the inherent capacitive coupling between the input and output circuits of said second control space discharge device, for obtaining a voltage substantially in phase opposition to said undesired voltage and for applying said last-named voltage to the input circuit of said first control space discharge device, the output circuit of said second control device being coupled to said resonant circuit in phase opposition to the output circuit of said first control device.

8. In an electrical system for forming frequency-controlled oscillations, means for generating self-sustained oscillations comprising a space discharge device and an associated resonant circuit including reactive elements, a control space discharge device having an input circuit and an output circuit, connections between said output circuit and said resonant circuit for connecting said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, and means including a second control space discharge device having an input circuit and an output circuit with inherent capacitive coupling therebetween, said last-named output circuit being connected in phase opposition to said first-named output circuit, for obtaining a voltage substantially in phase opposition to said undesired voltage and for applying said last-named voltage to the input circuit of said first control discharge device.

9. In a superheterodyne radio receiver including a first detector and an intermediate frequency amplifier, means connected to said amplifier for forming a control voltage whose amplitude varies in accordance with mistuning of said receiver, a control space discharge device having an input circuit and an output circuit, means for applying said control voltage to said input circuit, a second space discharge device and a resonant circuit associated therewith for generating self-sustained oscillations, means for coupling said output circuit in operative relation with at least a portion of a reactance of said resonant circuit, means for obtaining a signal voltage in phase quadrature relation with the voltage across said output circuit and for applying said quadrature voltage to said input circuit, there being inherent capacitive coupling between said input and output circuits whereby an undesired voltage in direct phase relation with said output circuit voltage is applied to said input circuit, means for obtaining a voltage substantially in phase opposition to said undesired circuit voltage and for applying said last-named voltage to said input circuit for opposing said undesired voltage, and

means for applying said oscillations to said detector.

10. In a superheterodyne radio receiver including a first detector and an intermediate frequency amplifier, a frequency sensitive circuit energized by said amplifier and adapted to form differential control voltages in accordance with the mistuning of said receiver, a pair of control space discharge devices each having an input circuit and an output circuit, means for applying said control voltages respectively to said input circuits, a third space discharge device and a resonant circuit associated therewith for generating self-sustained oscillations, means for connecting one of said output circuits in operative relation with at least a portion of a reactance of said resonant circuit, means for obtaining a signal voltage in phase quadrature relation with the voltage across said one output circuit and for applying said quadrature voltage to the associated input circuit, means connecting said input circuits and said output circuits in cooperative relation such that the inherent capacitive couplings of said control devices oppose one another, and means for applying said oscillations to said detector.

11. In an electrical system for forming frequency-controlled oscillations, a discriminator comprising a resonant circuit, means for supplying signal energy to said circuit, a second resonant circuit reactively coupled to said first resonant circuit, said second resonant circuit including an inductive element, a pair of diodes each having an anode and a cathode, a connection between each of said cathodes and said inductive element, a pair of serially connected resistances connected to said anodes of said diodes, a connection conductive to unidirectional currents between the midpoint of said inductive element and the common connection of said resistances, means for applying the voltage across said first resonant circuit between said diode anodes and said midpoint of said inductive element, a second pair of serially connected resistances connected to said diode anodes, and means for obtaining differential control signals from each of said second pair of resistances.

12. In an electrical system for forming frequency controlled oscillations, a resonant circuit including inductive and capacitive reactances, a space discharge device, connections between said device and said resonant circuit for adapting said device and said circuit to generate self-sustained oscillations, a control space discharge device having an input circuit and an output circuit, connections for coupling the output circuit to the resonant circuit, means for deriving a current in phase with the voltage across the resonant circuit, a control reactance, connections for applying the said current to the control reactance to form a voltage substantially in phase quadrature relation with the voltage across the resonant circuit, connections for supplying the quadrature voltage to the input circuit to form in the output circuit an effective reactance having an undesired resistive component, the control space discharge device, the current deriving means, the control reactance, and the connections for both the input and output circuits of the control tube forming a closed loop circuit, and a second closed loop circuit for minimizing said undesired resistive component, comprising means for deriving a voltage in direct phase relation with the voltage across the resonant circuit and means for supplying such voltage to the

input circuit, to form in the output circuit a resistive component of opposite polarity with respect to said first mentioned component.

13. In combination with a resonant tank circuit, a frequency control network comprising a pair of space discharge devices each including at least a cathode, a plate and a grid, an output circuit for one of said devices coupled to said tank circuit, another output circuit for the other of said devices coupled to said tank circuit in opposed relation to said first output circuit, a reactive path operatively associated with said tank circuit to derive alternating current voltage therefrom, means for impressing said voltage on each of the grids of said devices, and means for differentially biasing said grids in opposite polarity sense thereby to regulate the alternating current flow in said output circuits.

14. In combination with an oscillator provided with a tunable tank circuit, a frequency control tube having an output circuit which is coupled to said tank circuit, said control tube including at least two control grids, a reactive path operatively associated with said tank circuit to derive alternating voltage therefrom, means for impressing said voltage on said grids, and means for impressing direct current voltages upon said grids in opposite polarity sense thereby to regulate the alternating current flow in said control tube output circuit.

15. In combination with a resonant circuit tuned to a desired frequency, a frequency variation network including a pair of space discharge devices, each having an output electrode and space current controlling means, reactive means coupled to said resonant circuit for deriving therefrom alternating voltage substantially in phase quadrature with the voltage across said resonant circuit, a source of varying voltage in response to which the frequency of said resonant circuit is to be varied, means for connecting said output electrodes to said resonant circuit to apply the output voltage of said devices to the resonant circuit, means for connecting said reactive means to the space current controlling means of said devices to applying the quadrature voltage thereto, and means for connecting said source to the

space current controlling means of said devices to apply said varying voltage thereto, the voltages applied by two of the aforesaid connecting means being in opposite phase, and the voltage applied by the other of said connecting means being in the same phase.

16. In combination with an oscillator provided with a resonant tank circuit, a frequency control network including a pair of space discharge devices, each having an output electrode and space current controlling means, reactive means coupled to said resonant circuit for deriving therefrom alternating voltage substantially in phase quadrature with the voltage across said resonant circuit, means responsive to variations of the oscillator frequency for producing control voltage, means for connecting said output electrodes to said resonant circuit to apply the output voltage of said devices to the resonant circuit, means for connecting said reactive means to the space current controlling means of said devices to apply the quadrature voltage thereto, and means for connecting said control voltage-producing means to the space current controlling means of said devices to apply the control voltage thereto, the voltages applied by two of the aforesaid connecting means being in opposite phase, and the voltage applied by the other of said connecting means being in the same phase.

17. In combination with a resonant circuit tuned to a desired frequency, a frequency variation network comprising a pair of space discharge devices each including an anode and space current controlling means, an output circuit for said devices coupled to said resonant circuit, said anodes being connected to a common point of said output circuit, reactive means coupled to said resonant circuit to derive alternating voltage therefrom, means for applying said voltage to the space current controlling means of said devices in opposite phase relation to control the space current therein, and means for applying differentially-varying potentials to the space current controlling means of said devices to further control the space current therein.

CHARLES TRAVIS.
